ARTHUR K. LAUKEL, OF DETROIT, MICHIGAN

METHOD OF REENFORCING HOLLOW BODIES FORMED BY ELECTRODEPOSITION

Application filed June 21, 1928. Serial No. 287,316.

The present invention pertains to a novel method of reenforcing hollow bodies formed by deposition and is adapted particularly for use in connection with the manufacture of patterns by electro-deposition.

5 Such bodies or patterns are preferably comprised of an electro-deposited shell which is subsequently filled with suitable material. It is desirable to maintain the deposited shell at a minimum thickness, consistent with 10 strength, thereby reducing the amount of time, current and material required in the electro-plating process. The cathode on which the deposit forms is in the nature of a mold from which the deposit must be separated when finished. It has been found in 15 practice that the deposit must have a definite rigidity, especially at certain points, in order to avoid distortion when the mold is removed.

The object of the present invention is to 20 provide a means for furnishing such rigidity as well as anchorage for dowel pinning and screwing, and consists essentially in depositing a bridge across the depression of the mold at those points where reenforcement is desired. The bridge is preferably built of a 25 plastic non-conducting material when the deposition has been partly completed. The outer surface of the bridge is rendered conductive, and the plating operation is continued, whereby a deposited bridge forms as 30 an integral part of the hollow body. The plastic bridge may then be removed, while the deposited bridge remains as a reenforcement of the hollow body.

35 Where the bridge is to be used as anchorage for a dowel pin or screw, it is made sufficiently thick for this purpose and obviously is retained as a permanent part of the deposit. Such a bridge may consist of a metallic insert, 40 such as brass, united to the main deposit by deposited metal.

The invention is fully disclosed by way of example in the following description and in the accompanying drawings, in which—

45 Figure 1 is an elevation of a mold or cathode prepared for plating;

Fig. 2 is a transverse section of the mold after the first stage of plating;

50 Fig. 3 is a plan view of the mold after the

first stage of plating and with the insulator removed and the plastic bridges inserted;

Fig. 4 is a section on the line 4—4 of Figure 3;

Fig. 5 is a section on the line 5—5 of Figure 3;

Fig. 6 is an elevation of the mold after the plating has been completed;

Fig. 7 is a section on the line 7—7 of Figure 6;

Fig. 8 is a section on the line 8—8 of Figure 6;

Fig. 9 is a perspective view with the mold and the complete deposit therein, the latter being severed for separation from the deposit; and

Fig. 10 is a sectional view similar to Figure 8 showing a bridge built up in a somewhat different manner.

Reference to these views will now be made by use of like characters which are employed to designate corresponding parts throughout.

In Figure 1 is illustrated a mold 1 of suitable material formed with a depression or cavity 2, the face of which is rendered conductive and connected to the negative side of an electric circuit in order to function as a cathode. The preparation of the mold is described in my co-pending application, Serial 108,715, filed May 13, 1926. Over the face of the mold is applied an insulating sheet 4 having its edges projecting slightly over the depression. This insulator is retained on the cathode during the initial stages of plating in order to prevent the formation of any deposit above the edge of the depression. This condition is illustrated in Figure 2 which shows a deposit 5 formed in the depression but diminishing in thickness towards the edges and not extending beyond the edges.

The cathode is now withdrawn from the bath in order that the insulator 4 may be removed. Bridges 6 are built across the depression at points where reenforcement is desired for the purposes already stated. These bridges are preferably made of plastic material such as wax and coated with graphite on the upper or outer surface in order to attract the ions of the metal in the bath. It

will be seen in Figure 4 that the top of the bridge is substantially flush with the face of the mold, so that the deposited bridge will for the most part lie over the face of the mold.

At points where it may be necessary to drive fastening elements through the deposited body, such as screws through a pattern, the bridge 6' is in a lower plane and has its upper surface beneath the face of the mold as shown in Figure 5. Another means of forming anchorage for dowel pins or screws is illustrated in Figure 10 wherein a small block of metal 11, such as brass, is inserted in the deposit and secured to the walls thereof by plastic material 12. The top of the plastic material is preferably below the top of the insert. The upper surface of the plastic material is rendered conductive, as is the top of the insert if necessary, in the manner described.

The mold is now returned to the bath and electro-plating is resumed until the desired deposit is built up. The complete deposit is shown in Figures 6 to 9, wherein a strengthening flange 7 is formed exteriorly around the edge of the deposit and wherein deposited bridges 8 are formed over the plastic bridges 6. If, however, no flange is to be deposited, the insulator 4 need not be removed prior to the second immersion, but it is only necessary to notch the edges of the insulator at the points where the bridge is to be united to the initial deposit. Where a sunken bridge 6' has been provided a thicker deposited bridge 9 forms thereon and obviously extends for some distance below the face of the mold. In connection with the method illustrated in Figure 10, a deposit 13 forms over the top and partly covers the ends of the insert 11.

The mold or cathode is now severed along various lines as indicated by the numeral 10 whereby it may be broken away from the deposit. The breaking action causes certain stresses on the deposit, and to resist these stresses the deposit must have such reenforcement as has been described.

The subsequent treatment of the deposit, in case it is a pattern, consists in filling it with a cheap, low fusing metal and then machining off the flange 7 to form a plane parting surface. This operation substantially removed the bridges 8, but it will be understood that these bridges have already served their purpose and are not actually necessary in the finished pattern. The heavier bridges 9 which have been formed for the purpose of anchoring fastening elements obviously remain to the extent of the portion lying beneath the parting surface.

Although the invention has been developed particularly for use in connection with the deposition of patterns, it is obviously useful in the formation of other hollow bodies

which may be deposited by the same process. The cathode bridges have been described as consisting of a plastic material coated with graphite, but there is no restriction to this composition, for the bridges may be formed in any manner and of any material which will provide the desired transverse conductive strip on which a permanent bridge may be deposited. Various other modifications of the disclosed operations may be made without departing from the scope of the invention as indicated by the appended claims.

What I claim is:—

1. In the process of forming a hollow metallic body on a depressed mold by electro-deposition, the operation consisting in building across the depression at a point where reenforcement is desired, a bridge having a conductive surface, whereby a metallic bridge is deposited integrally with the hollow body. 70
2. In the process of forming a hollow metallic body on a depressed mold by electro-deposition, the operation consisting in building a bridge of non-conducting material across the depression at a point where reenforcement is desired, and rendering the surface of said bridge conductive, whereby a metallic bridge is deposited integrally with the hollow body. 75
3. A method of making reenforced metal hollow bodies consisting in electro-deposition a depressed mold to a portion of the desired thickness of deposit, building across such partial deposit at a point where reenforcement is desired, a bridge having a conductive surface, and continuing the plating whereby a metallic bridge is deposited integrally with the hollow body. 80
4. A method of making reenforced metal hollow bodies consisting in electro-deposition a depressed mold to a portion of the desired thickness of deposit, building a bridge of non-conductive material across the depression at a point where reenforcement is desired, rendering the surface of said bridge conductive, and continuing the plating whereby a metallic bridge is deposited integrally with the hollow body. 85
5. In the process of forming a hollow metallic body on a depressed mold by electro-deposition, the operation consisting in building a bridge of wax across the depression at a point where reenforcement is desired, and rendering the surface of said bridge conductive, whereby a metallic bridge is deposited integrally with the hollow body. 90
6. In the process of forming a hollow metallic body on a depressed mold by electro-deposition, the operation consisting in supporting a metal insert across the mold and plating upon said insert and between the insert and the mold, whereby a metallic bridge is formed and united to the hollow body by deposited metal. 95
7. In the process of forming a hollow me- 130

tallic body on a depressed mold by electro-deposition, the operation consisting in supporting a metal insert across the mold by plastic material, rendering the surface of said

5 material conductive, and plating on said insert and material, whereby a metallic bridge is deposited integrally with the hollow body.

8. In the process of forming a hollow metallic body on a depressed mold by electro-deposition, the operation consisting in building 10 a bridge of wax across the depression at a point where reenforcement is desired, and applying graphite over the surface of said bridge, whereby a metallic bridge is deposited 15 integrally with the hollow body.

9. A cathode for the formation of a hollow body by electro-deposition, comprising 20 a mold having a depression therein, the wall of said depression being conductive, and a bridge built across said depression at a point where reenforcement is desired, said bridge having a conductive outer surface.

In testimony whereof I affix my signature.
ARTHUR K. LAUKEL.
